BOOT

David Cupples and Eleanor Cupples, both of 823 Broadway Ave., Saskatoon, Saskatchewan, Canada

Filed June 1, 1972, Ser. No. 258,929

Claims priority, application Canada Dec. 2, 1971

Term of patent 14 years

Int. Cl. D2—04

U.S. Cl. D2—272

The single figure of drawing is a perspective view of our design for a boot; the opposite side is identical except for the absence of the bow and tassels.

We claim:

The ornamental design for a boot, as shown and described.
